TONE CONTROL MEANS

William S. Bachman, Fairfield, Conn., assignor to
 General Electric Company, a corporation of
 New York

Application February 19, 1942, Serial No. 431,587

7 Claims. (Cl. 178—44)

My invention relates to tone control means and more particularly to such means for effecting manual control of the high frequencies in the audio range.

It has for one of its objects to provide improved means for controlling the high frequency response of an audio frequency system such as the audio amplifiers used in common household radio receivers.

Another object of my invention is to effect such means without materially increasing the cost of the system.

The novel features which I believe to be characteristic of my invention are set forth with particularity in the appended claims. My invention itself, however, both as to its organization and method of operation, together with further objects and advantages thereof may best be understood by reference to the following description taken in connection with the drawing in which Fig. 1 represents an embodiment of my invention; Figs. 2 and 3 represent certain modifications thereof, and Fig. 4 represents certain characteristics pertaining to the invention.

Referring to Fig. 1 of the drawing, I have represented at 1 therein an electron discharge device which may be utilized, for example, as a detector and first audio frequency amplifier of a radio receiver. This discharge device comprises a cathode 2 and an anode 3. Signals of radio frequency to be detected may be supplied to a tuned circuit 4 connected between the anode 3 and the cathode 2 through the usual detector load resistance 5, which is shunted by the usual condenser 6. The circuit 4 may comprise, for example, the last tuned circuit in the intermediate frequency portion of a superheterodyne receiver, for example, upon which modulated currents of the intermediate frequency appear. These currents are rectified by the diode comprising electrodes 2 and 3 and the audio frequency potentials, which may be of voice or music frequencies, appear upon the resistance 5. Across this resistance is connected a volume control resistance 7 through the large coupling condenser 8. A variable tap 9 on this resistor 7 is connected through condenser 10 to the control electrode 11 of the discharge device 1. This control electrode is connected to the cathode of the discharge device by means of a resistance 12.

Thus voice or music currents appearing on resistance 7 are amplified in the amplification section of the discharge device 1 and appear upon the anode 13 and are supplied to any suitable load device, which may comprise additional

stages of amplification and ultimately a loud speaker.

The intensity or volume of the current so amplified is controlled by variations of the slider 9 along the potentiometer 7. To effect control of the amplification of the high frequency current with respect to the amplification of the low frequency currents, the path comprising resistance 14, condenser 15, resistance 16 and condenser 17 is provided between the tap 9 and ground, a variable point 18 on the resistance 16 being connected to the ungrounded terminal of the resistance 5.

When the tap 18 is at the top, or upper end 15 of the resistance 16 as shown in the drawing, high frequency currents are supplied through the condenser 15 and resistance 14 to the tap 9 on resistance 7. Thus high frequencies are supplied directly to amplifier 1 without any attenuation by potentiometer 7, 9. When slider or variable point 9 is at any intermediate point on the resistance 7 this connection 15, 14 serves to supply a greater volume of the high frequency currents to the amplifier and thus increases the amplification of the high frequency currents relative to the low frequency currents, the extent of this increase being, of course, dependent upon the value of condenser 15 and the magnitude of resistance 14. As tap 9 is moved downward the ratio of response at high frequencies to that at low is progressively increased.

When slider 18 is moved downward on resistance 16, this increased amplification is reduced both by insertion of the upper portion of resistance 16 in series with condenser 15 thereby reducing the extent to which high frequency currents are supplied to contact 9, and also by reducing the portion of resistance 16 in series with condenser 17 thereby increasing the extent to which high frequency currents are bypassed by that condenser. When contact 18 reaches the bottom of the resistance condenser 17 is connected directly across resistance 5. When this occurs the response at high frequencies may be substantially nil.

Fig. 4 represents, by way of example, certain frequency response characteristics obtained on a particular receiver having a tone control system such as that shown in Fig. 1. The curves of the figure are plotted with the output of the receiver in decibels as ordinates and frequency as abscissa. The curve A of this figure represents the response which exists when the tone control tap 18 is at the upper end of the resistance 16. It will be seen that the response of the receiver

is maximum at a frequency of, for example, 4,000 cycles, and is greater than at low frequencies. This curve corresponds to a condition in which the resistance 14 is omitted from the circuit. If resistance 14 of desired value be inserted the response may be more nearly as indicated by the curve B. If the contact 18 be moved downward on resistance 16 to the mid-point, the frequency response curve may be then indicated at C in which the high frequency response is shown as very greatly reduced with respect to that shown by curve A. If the tone control contact 18 be moved to the lower terminal of resistance 16, the response is as indicated by the curve D of Fig. 4 in which it will be seen that response at frequencies above 4,000 cycles is very small.

These curves of Fig. 4 apply when contact 9 on resistance 7 is at an intermediate point on that resistance. As contact 9 is moved downwardly on resistance 7 the effect of circuit 14, 15, 16 in accentuating the high frequencies relative to the low frequencies is increased as the signal is reduced. Of course, the extent to which this increase occurs is dependent upon the values of the various circuit components employed. One set of values found satisfactory is as follows:

Resistance 7 = 2 megohms
 Resistance 16 = 2 megohms
 Resistance 14 = 180,000
 Capacity 8 = .005 microfarads
 Capacity 15 = .0001 microfarads
 Capacity 17 = .005 microfarads

Fig. 2 is substantially the same as that shown in Fig. 1 with the resistance 14 omitted. The signal source is represented in this figure at 20 and as having internal resistance indicated at 20'.

Fig. 3 differs from Fig. 2 in that the tone control network 15, 16, 17 is connected between a fixed point 21 on resistance 7 and ground. An additional network employed for bass compensation, comprising a resistance 22 and a condenser 23 in series, is also connected between this point 21 and ground. These latter elements are proportioned in the manner of the usual bass compensation network and by-pass a portion of the high frequency currents, thereby to increase the response at very low frequencies as, for example, frequencies below 400 cycles.

In this figure the effect of the bass compensation network 22, 23 and that portion of the tone control network comprising capacitance 15 and the portion of resistance 16 above the variable point 18, which increases the high frequency response, is effective only when contact 9 is on the part of resistance 7 below tap 21. The condenser 17 and the lower part of resistance 16 below contact 18 is effective to reduce the highs, however, irrespective of the position of contact 9.

While I have shown particular embodiments of my invention it will, of course, be understood that I do not wish to be limited thereto since certain modifications may be made therein and I contemplate by the appended claims to cover any such modifications as fall within the true spirit and scope of my invention.

What I claim as new and desire to secure by Letters Patent of the United States is:

1. In combination, a source of audio frequency currents, an impedance connected across said source having a tap, a utilization circuit connected between one side of said source and said tap, a condenser and a resistance connected in series across said utilization circuit and a con-

nexion from the other side of said source to a point variable along said resistance.

2. In combination, a source of audio frequency current, an impedance connected across said source having a tap, a utilization circuit connected between one side of said source and said tap, a condenser and a resistance connected in series between said one side of said source and an intermediate point of said impedance, said 10 condenser being adjacent said one side of said source, and a connection from the other side of said source to a point variable along said resistance.

3. In combination, a source of audio frequency currents, a first resistance connected across said source having a tap, a load device connected between one terminal of said resistance and said tap, a second resistance and condenser connected in series between said one terminal and an intermediate point on said first resistance, and a connection from the opposite terminal of said first resistance to a point variable along said second resistance, said condenser being positioned between said second resistance and said one terminal and proportioned to by-pass currents of frequency high in the audio range when said variable point on said second resistance approaches the terminal connected to said condenser.

4. In combination, a source of currents having frequencies extending throughout the voice range, a potentiometer connected thereacross having output terminals one of which comprises a tap variable thereon, a resistance and a condenser connected in series between an intermediate point on said potentiometer and the other of said output terminals in the order mentioned and a variable tap on said second resistance connected to the side of said source opposite said other terminal, said condenser being proportioned to by-pass currents having frequency high in said range whereby movement of said variable tap affects oppositely the extent to which said currents are by-passed by said condenser and the extent to which they are supplied from said tap to said first resistance.

5. In combination, a source of currents having a wide range of audio frequencies, an impedance connected across said source, a load connected between one terminal of said impedance and a variable tap thereon, a resistance and a pair of condensers, said resistance having one point thereon connected through one of said condensers to said one terminal and having another point connected through the other of said condensers to an intermediate point on said impedance, and a connection from the opposite terminal of said impedance to a contact variable along said resistance between said two points thereon, whereby when said variable contact is at one of said points said one condenser forms a by-pass for high frequency currents across said source and said resistance impedes the flow of high frequency currents through the other condenser and when said contact is moved from said point along said resistance toward said other point, said resistance reduces the effect of said by-pass and increases the effect of said other condenser.

6. In combination, a source of voice or music frequencies, an impedance connected across said source, a load connected between one terminal of said source and a tap variable on said impedance for volume control, and means to vary the degree to which high frequency currents are supplied from said source to said load, said means

comprising a condenser, a resistance and a second condenser connected in series in that order between said first tap and said one terminal, and a connection from the other terminal of said source to a tap variable along said resistance whereby high frequency currents are alternatively by-passed across said source by the first of said condensers or transmitted to said first tap by said second condenser both in varying degrees in accordance with the variations in position of said second tap.

7. In combination, a source of voice or music frequencies, an impedance connected across said source, a load connected between one terminal of said source and a tap variable on said impedance for volume control, and means to vary the degree to which high frequency currents are supplied

from said source to said load, said means comprising a condenser, a resistance and a second condenser connected in series in that order between a second tap on said impedance and said one terminal and a connection from the other terminal of said source to a contact variable along said resistance, whereby high frequency currents are alternatively by-passed across said source by one of said condensers or transmitted to said second tap by the other of said condensers both in varying degrees in accordance with variations in the position of said contact, and an additional resistance and condenser connected in series between said second tap and said one terminal to by-pass high frequency currents.

WILLIAM S. BACHMAN.
